Primary Examiner — Kevin Rudzinski*Assistant Examiner* — John Reickel(74) *Attorney, Agent, or Firm* — Goodwin Procter LLP(57) **CLAIM**

The ornamental design for a computer display with graphical user interface, as shown and described.

DESCRIPTION

The sole FIGURE is a front view of a computer display with graphical user interface.

The broken line showing of a computer display and elements of a user interface is included for the purpose of illustrating portions of the article and forms no part of the claimed design.

1 Claim, 1 Drawing Sheet(56)
